UNITED STATES PATENT OFFICE

142,283

DESIGN FOR A BABY FOOD WARMER

Max Hirsch, New York, N. Y.

Application November 4, 1944, Serial No. 116,143

Term of patent 14 years

(Cl. D44—15)

To all whom it may concern:

Be it known that I, Max Hirsch, a citizen of the United States, residing in New York, New York, have invented a new, original, and ornamental Design for a Baby Food Warmer, of which the following is a specification, reference being had to the accompanying drawing, forming part thereof.

I claim:

The ornamental design for a baby food warmer, as shown.

MAX HIRSCH.
